GOLF BALL POSITION MARKER

Keith B. Thayer, 3839 Buffalo Speedway,
Houston 6, Tex.

Filed June 7, 1963, Ser. No. 75,267

Term of patent 14 years

(Cl. D34—5)

FIG. 1 is a perspective view of the top side of a golf ball position marker embodying my design;

FIG. 2 is a perspective view of the bottom side of the golf ball position marker of FIG. 1;

FIG. 3 is a top plan view on a reduced scale; and

FIG. 4 is a side elevational view with a golf ball shown in broken lines for illustrative purposes only.

I claim:

The ornamental design for a golf ball position marker, substantially as shown and described.
